UNITED STATES PATENT OFFICE.

WALTER REICHEL AND GUSTAV KARL HENNIG, OF BÖHLITZ-EHRENBURG, NEAR LEIPZIG, GERMANY, ASSIGNEES TO LUDWIG HUPFELD AKTIENGESELLSCHAFT, OF BÖHLITZ-EHRENBURG, NEAR LEIPZIG, GERMANY.

NOTE-SHEET-CHANGING DEVICE FOR PNEUMATIC MUSICAL INSTRUMENTS.

1,158,288.

Specification of Letters Patent.

Patented Oct. 26, 1915.

Application filed May 4, 1914. Serial No. 836,214.

To all whom it may concern:

Be it known that we, WALTER REICHEL, a subject of the King of Saxony, residing at Gutenbergstrasse, Böhlitz-Ehrenberg, near 5 Leipzig, Germany, and GUSTAV KARL HENNIG, a subject of the King of Saxony, residing at 1 Bielastrasse, Böhlitz-Ehrenberg, near Leipzig, Germany, have invented certain new and useful Improvements in 10 Note-Sheet-Changing Devices for Pneumatic Musical Instruments; and we do hereby declare the following to be a full, clear, and exact description of the invention, of which the following is a specification.

15 This invention relates to a device for pneumatic musical instruments played by means of note sheet rolls.

The device not only enables the musical instrument to be played continuously but 20 it also allows during this playing of changing the piece to be played. For this purpose a carrier for note sheets preferably a drum of a kind well known, carrying two or more rolls of note sheets is employed, on 25 which are arranged the sheets to be played; these rolls can be brought in turn in a well known manner into the playing position.

It has heretofore been proposed to draw the note sheets of such a magazine carrying 30 several rolls over a tracker bar arranged outside the magazine and to lead them to a winding-up roller.

The device according to this invention differs from known devices of this type in 35 that instead of one winding-up roll being provided for all the note sheet rolls several winding-up rollers are provided which can operate in turn and each of which draws one note sheet over a tracker bar while a 40 sheet which has been played can be rewound. In this manner a note sheet change device is provided such that it is no longer necessary to wait for the music which has been played to be rewound, but one roll can be 45 played after the other without interruption. The rolls may contain parts of very long pieces or different pieces as desired.

Several illustrative embodiments of the invention are diagrammatically represented 50 by way of example in the accompanying drawing, wherein:

Figure 1 is an elevation showing a note

sheet winding up device comprising a rotatable arm carrying two rollers. Fig. 2 is a like view showing another form of the device in which the carrier of the winding up rollers is star-shaped. Fig. 3 shows a third form comprising a number of winding up rollers displaceable in an oval guide, and Fig. 4 shows a fourth form comprising two winding up rollers disposed at the two sides of the magazine of the note sheet rolls.

Referring first to Fig. 1, a number of note sheets wound on rolls a^1 to a^6 are arranged on a rotatable drum-shaped magazine b of known construction. The carrier is rotatable in known manner about the axle b^1 of a stationary frame b^2 . A rotatable arm c mounted on the axle c^1 journaled in a stationary frame c^2 is provided separate from the magazine. Winding up rollers d^1 and d^2 are mounted on the two ends of this arm. Between the rotatable arm c and the magazine b is a tracker bar e over which the sheet o to be played is passed, as indicated by the full line. The tracker bar is mounted in any desired suitable manner and is provided, as usual, with tubular connections e^1 which lead to the instrument to be played.

The sheet o is conveyed from the rolls a^1 to a^6 of the magazine to the winding up rollers d^1 , d^2 by known means and the driving mechanism for playing and rewinding the note sheets is also known, so that the parts of the mechanism in question are not shown in the drawing. When the sheet o has been played the drum is turned in the direction of the arrow until the roll a^2 arrives into the position previously occupied by the roll a^1 . The arm c is turned 180° at the same time so that the roller d^2 occupies the position previously occupied by the roller d^1 . The sheet then occupies the position shown in the dotted lines and can now be rewound on its roll a^1 which now occupies the position previously occupied by the roll a^2 . At the same time as the sheet is being wound back on the roll a^1 the sheet of the roll a^2 is pulled over the tracker bar e and wound up on the roller d^2 . Consequently, the sheet of the roll a^2 is played while the sheet of the roll a^1 is being rewound. All the sheets can thus be played in turn without having to wait for the sheet

which has just been played being wound back. The rotatable carrier *c* of the winding-up rollers *d*¹, *d*² can be secured in its position at any time by any suitable locking device, *e. g.* by means of a spring-pressed pin *f* which snaps into recesses in a disk *f*¹.

Referring now to Fig. 2, the rotatable carrier for the winding-up rollers may carry 10 several such rollers instead of only two thereof. Preferably the carrier will carry as many rollers as the magazine has note sheet rolls. As shown in the figure, the carrier *c*³ for the rollers *d*¹ to *d*⁶ may be 15 formed exactly like the carrier of the magazine. In the same manner the carrier *c*³ can be locked in its position by means of a spring-pressed pin *f*.

In the embodiment shown in Fig. 3 the 20 note sheet rolls and the winding-up rollers are displaceable in oval guides *p* and *q*, respectively. The rollers *d*¹ to *d*⁸ are displaceable in the guide *p* and the rolls *a*¹ to *a*⁸ in the guide *q*. The note sheet rolls and 25 the winding-up rollers are shifted simultaneously by means of gear-wheels *p*¹ and *q*¹ which when rotating in the direction indicated by the arrows engage with the axles of the rolls *a* and rollers *d* and with the intermediate antifriction rollers *p*² and *q*² 30 slidable in the oval guides. After a sheet *o* which is pulled over the stationary tracker bar *e* has been played, the note sheet rolls and rollers are shifted in such manner that 35 one sheet is always ready for being played on the tracker bar located between the guides, while the sheet which has been played and is removed from the tracker bar is being rewound as indicated by dotted 40 lines.

In the embodiment shown in Fig. 4 the winding up rollers *d*¹, *d*² are not arranged on one common carrier, but are rotatably mounted apart at the two sides of the magazine on separate stationary supports *c*⁴, *c*⁵. In this case separate tracker bars *e*¹, *e*² are provided for each roller *d*¹, *d*², respectively. The two tracker bars may act on the same or on several musical instruments, *e. g.* 45 piano, violin or the like, and can be brought into and out of operative connection with the same, so that only that tracker bar of the sheet just being played is connected with a musical instrument.

50 When the sheet *o*¹ is being played, it is in the position indicated in full lines and is being unwound from roll *a*¹ onto roll *d*¹, the tracker bar *e*¹ being connected with the musical instrument. During the playing of sheet *o*¹, sheet *o*² is in the position indicated by dotted lines *o*² and is being unwound from roll *d*² onto roll *a*⁴, the tracker *e*² being disconnected from the instrument. At the 55 end of the playing of sheet *o*¹ and the unwinding of sheet *o*², the tracker bar *e*¹ is

disconnected, the tracker bar *e*² connected to the musical instrument, and the carrier *b* rotated to bring the roll *a*¹ into the position indicated by roll *a*² on the drawing, and the sheet *o*¹ will be unwound from roll *d*¹ back 70 onto roll *a*¹, as indicated by the dotted line *o*¹ and out of playing position. The rotation of the carrier *b* brought the roll *a*² into the position indicated by roll *a*³ and the sheet *o*² being in playing position, as indicated by the full line *o*², is unwound from roll *a*² onto roll *d*². 75

When the sheet *o*² on roll *a*² has been played, the carrier *b* is again rotated the distance between two rolls so that the roll *a*² 80 is moved into the position indicated by roll *a*⁴ and the roll *a*⁵ will be in the position indicated by roll *a*¹. Thus, if the sheet on roll *a*¹ is first played over the tracker bar *e*¹, the sheet on roll *a*² is next played over 85 tracker bar *e*² and after the sheet on roll *a*² has been played the sheet on roll *a*⁵ will next be played over tracker-bar *e*¹, said roll *a*⁵ being brought into playing position when the roll *a*² is brought into position for rewinding, *i. e.* the position of roll *a*⁴ shown 90 on the drawing.

We claim as our invention:

1. A note sheet changing device for pneumatic musical instruments comprising a carrier, a plurality of rolls of note sheets mounted thereon, a plurality of winding rolls independent of the carrier, and means located between the latter and said winding rolls for controlling the playing of the musical instrument when the note sheet to be played passes over it. 95

2. A note sheet changing device for pneumatic musical instruments, comprising a rotatable carrier for a plurality of note sheet rolls, an independent movable carrier for a plurality of winding rolls, and a tracker bar located between said carriers for controlling the playing of the musical instrument when a note sheet to be played passes over it. 100

3. A note sheet changing device for pneumatic musical instruments, comprising a rotatable carrier for a plurality of note sheet rolls, a separate rotatable carrier for a plurality of winding up rolls, and a tracker bar located between said carriers for controlling the playing of the musical instrument when a note sheet to be played passes over it. 115

4. A note sheet changing device for pneumatic musical instruments, comprising a rotatable carrier for a plurality of note sheet rolls, a separate movable carrier for a plurality of winding up rolls, means for locking the latter carrier in operative positions at any time, and a tracker bar located between said carriers for controlling the playing of the musical instrument when a note sheet to be played passes over it. 120

5. In a note sheet changing device for pneumatically actuated musical instruments, 130

a movable carrier for holding a plurality of note sheet rolls, winding rolls separate therefrom, a tracker bar between the carrier and winding rolls, different note sheet rolls co-operating with different winding rolls.

6. In a note sheet changing mechanism for pneumatically actuated musical instruments, the combination with a movable magazine for a plurality of note sheet rolls, and a 10 tracker bar, of a plurality of winding rolls, one of which is arranged to withdraw a note sheet from a roll in the magazine over the tracker bar during the time that another of said winding rolls is delivering a previously 15 played sheet for rewinding out of playing position and distant from said tracker bar.

7. In a note sheet changing mechanism for pneumatically actuated musical instruments, 20 a movable carrier for a plurality of note sheet rolls, and winding rolls separate from the carrier, one of the rolls in the carrier positioned to unwind onto a winding roll for

playing the instrument and another roll on the carrier positioned to simultaneously receive 25 a note sheet from a winding roll.

8. In a note sheet changing mechanism for pneumatically actuated musical instruments, a movable carrier for a plurality of note sheet rolls, a plurality of winding rolls independent of the carrier, one of said note sheet rolls co-operating with a winding roll in the tracking position of a note sheet for playing the piece, and another of said winding rolls co-operating with another of said note sheet 35 rolls, while out of tracking position, for simultaneously rewinding a previously played note sheet.

In testimony whereof we have signed our names to this specification, in the presence of 40 two subscribing witnesses.

WALTER REICHEL.

GUSTAV KARL HENNIG.
